US0D1072779S

(12) **United States Design Patent** (10) Patent No.: **US D1,072,779 S**
(45) Date of Patent: ** Apr. 29, 2025

(54) **BLUETOOTH TRANSCEIVER**

(71) Applicant: **ShenZhen Ankbit Electronics Limited**, Shenzhen (CN)

(72) Inventor: **Junkui Chen**, Shenzhen (CN)

(73) Assignee: **ShenZhen Ankbit Electronics Limited**, Shenzhen (CN)

(**) Term: **15 Years**

(21) Appl. No.: **29/878,791**

(22) Filed: **Jun. 27, 2023**

(51) LOC (15) Cl. **14-03**

(52) U.S. Cl.

USPC **D14/155**

(57) **CLAIM**

The ornamental design for a Bluetooth transceiver, as shown and described.

DESCRIPTION

FIG. 1 is a front view of a Bluetooth transceiver, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

The broken lines in the drawings illustrate the portions of the Bluetooth transceiver, which form no part of the claimed design.
